Primary Examiner — Vy N Koenig*Assistant Examiner* — Qiawen W Wiechert(74) *Attorney, Agent, or Firm* — Bayramoglu Law Offices LLC(57) **CLAIM**

The ornamental design for a camp bed, as shown and described.

DESCRIPTION

FIG. 1 is a perspective view of a camp bed showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof in a folded configuration.

The broken lines in the drawings depict portions of the camp bed that form no part of the claimed design.

1 Claim, 8 Drawing Sheets(56)
